UNITED STATES PATENT OFFICE.

WILLIAM D. FAIDLEY, JR., OF CLIFTON FORGE, JOHN W. MORRIS, OF IRON GATE, AND
SAMUEL A. PATTERSON, OF CLIFTON FORGE, VIRGINIA.

MACHINE FOR REMOVING AND REPLACING METAL PARTS OF TRAIN-PIPE
COUPLINGS.

Application filed December 27, 1921. Serial No. 524,910.

To all whom it may concern:

Be it known that we, WILLIAM D. FAIDLEY, Jr., residing at Clifton Forge, Alleghany County, Virginia, JOHN W. MORRIS, residing at Iron Gate, Alleghany County, Virginia, and SAMUEL A. PATTERSON, residing at Clifton Forge, Alleghany County, Virginia, citizens of the United States, have invented certain new and useful Improvements in Machines for Removing and Replacing Metal Parts of Train-Pipe Couplings, of which the following is a specification.

This invention relates to machines for assembling train pipe couplings and for removing the metal parts thereof from worn or weak hose. The present invention relates particularly to the machine for which Letters-Patent No. 1,252,676, were granted to us January 8, 1918, the objects of the invention being to provide simple and efficient means for controlling and expediting the operation of the machine, to provide means for supporting the hose and preventing buckling of the same while the metal parts are being assembled therewith, to provide means for compressing the clamps about the hose, and to improve generally the construction and arrangement of the parts of the machine to the end that the efficiency and durability thereof may be increased without any increase in the cost of production or maintenance.

The invention is illustrated in the accompanying drawings and consists in certain novel features which will be hereinafter first fully described and then particularly pointed out in the appended claims.

In the drawings,

Fig. 1 is a front side elevation of a machine embodying the present improvements.

Fig. 2 is a plan view of the same, one clamp-puller being omitted.

Fig. 3 is a longitudinal section.

Fig. 4 is an end elevation thereof.

Fig. 5 is a central transverse section.

Fig. 6 is a rear side elevation.

Fig. 7 is an enlarged front elevation, with parts in section, of the hose clamp and co-operating parts.

Fig. 8 is a plan view of the coupling-head holder shown in Fig. 7.

Fig. 9 is an enlarged detail longitudinal section of the nipple-puller.

Fig. 10 is a view similar to Fig. 7 but showing the hose support employed in assembling the coupling.

Fig. 11 is a plan view of the coupling-head holder shown in Fig. 10.

Fig. 12 is a detail view of the nipple holder.

Fig. 13 is an end view of the hose support shown in Fig. 10.

Fig. 14 is a plan view of the lower member of the hose support shown in Fig. 10.

Fig. 15 is a rear elevation showing means whereby the clamp-forming jaws may be motor-controlled.

Fig. 16 is a plan view of the mechanism shown in Fig. 15.

Fig. 17 is an elevation of clamp-forming and holding jaws.

Fig. 18 is a plan view of the same.

Fig. 19 is a view similar to Fig. 18 but showing the jaws in a different position.

Fig. 20 is a side view showing another arrangement of the jaws.

Fig. 21 is a plan view of the arrangement shown in Fig. 20.

The bed or main frame 1 of the machine is supported by feet 2 at its ends. On the top of the bed, at one end thereof, is a fixed knife 3 and cooperating with said knife is a rocking or oscillating knife 4 which is carried by the upper end of a lever 5, said lever being fulcrumed in suitable bearings 6 on the top of the bed and extending downwardly from the bearings. The lower end of the lever 5 is pivotally connected to the outer end of a piston rod 7 which extends from a piston 8 fitted in a cylinder 9, said cylinder being supported in any convenient or preferred manner at the bottom of the bed. The piston is caused to reciprocate in the cylinder, preferably, by compressed air which is admitted to the cylinder at the ends thereof through branch feed pipes 10 which lead to and discharge into the opposite ends of the cylinder from a controlling valve 11 on the front side of the bed. It will be readily understood that the valve 11 is set to admit the motor fluid to one end of the cylinder and simultaneously permit it to exhaust from a port 11^a from the opposite end, and the lever 5 will be rocked in one or the other direction according to the direction of flow of the fluid to the cylinder and the resultant movement of the piston. Nor-

mally, the lever is in the position which holds the knife 4 raised and the piston is at or near the outer end of the cylinder. When the bolt in a compression or clamping band on a train-pipe coupling is to be cut, it is held manually upon the knife 3 and the lever 5 rocked so that the knife 4 is forced down upon the bolt which is then quickly cut through by the two knives.

10 The compressed air or other motive fluid is carried to the valve 11 by a supply pipe 12 which is mounted on the front of the bed and has a branch 13 extending transversely through the bed and communicating 15 through a coupling 14 with a main supply pipe 15. Pipes 16 and 16^a lead from a four-way valve 17 on the back of the bed to carry the motive fluid to other points of use. The stem of the valve 11 is equipped at its front 20 end with an angle lever, the upstanding arm 18 of which has one end of a spring 20 attached thereto, the opposite end of the spring being attached to a fixed point on the bed. The lateral arm 19 of the angle 25 lever is connected by a link 21 with a treadle or foot lever 22 which is fulcrumed upon a bracket 23 depending from the bed. When the treadle is depressed, the air will be admitted to the cylinder at the outer end thereof, the spring 20 being put under tension and the knife 4 being caused to cut through the bolt. When the pressure upon the treadle is released, the spring at once contracts so that the valve is turned in the opposite direction and all the parts returned 30 to normal position. The inner end of the cylinder 9 is closed by a head 24 which is common to a larger cylinder 25, the purpose of which will hereinafter appear. The said cylinder 25 is constructed with a foot 26 constituting an intermediate support for the entire machine.

45 The flat top or table 27 of the bed is constructed with longitudinal slots 28 at or near its opposite ends and is so formed as to provide the longitudinal ways or guides 29 at the opposite sides of the slots. Carriers 30 are slidably fitted to the ways 29, one being equipped with means for supporting and securing the train-pipe coupler head, and the other being provided with a pin or similar device for supporting the nipple which, in actual practice, forms the connection between the train line and the hose of the coupling. Upon each carrier there is 50 also mounted a hose-clamp puller 31. Within the bed there are pivotally mounted the rocking arms or levers 32, 33, each of which has its upper end extended through one of the slots 28 and joined to the adjacent carrier by a pin and slot connection, as shown at 34, the lower end of the lever 33 being connected with a piston rod 35 in a similar manner, as shown at 36. A link 37 has one 55 end pivoted to the lever 33 above the ful-

crum thereof and its opposite end pivoted to lever 32 below the fulcrum thereof, the result of such arrangement being that the levers will be caused to rock simultaneously but in opposite directions and the carriers, 70 consequently, will approach or recede. The piston rod 35 extends from the piston 38 within the cylinder 25, and the movement of said piston obviously actuates the lever 33, the motion being transmitted through 75 the link 37 to the lever 32. The piston 38 is driven by compressed air admitted to the cylinder 25, at the ends thereof, through branch feed pipes 39 which are connected by a controlling valve 40 which, in turn, is connected with the supply pipe 12 through a nipple or coupling 41, the casing of the valve 40 being constructed with an exhaust port 40^a which communicates with one or the other pipe 39 according to the position of 80 the valve.

A lever or handle 42 is provided to permit the operator to easily set the valve 40 and control the direction of movement of the piston 38. The piston rod 35 extends axially through a bumper box 43 which is, preferably, formed integral with a foot 2, the outer end of the box being open and the inner end thereof being closed except for the bearing or guide in which the piston rod slides. The outer extremity of the piston rod is threaded and a stop collar or abutment 44 is adjustably mounted thereon, a spring 45 being coiled around the piston rod between the abutment and the inner 95 closed end of the box. Obviously, the tension of the spring may be regulated by adjusting the stop collar longitudinally of the piston rod. When the rod moves outwardly, the spring expands but when the rod moves inwardly the spring is compressed and, consequently, cushions the return stroke and prevents forcible contact between the lever 32 or the lever 33 and the bed at the end of the stroke and takes up the shock 100 when the fittings are pulled out of old hose. An elastic buffer block 46 on the opposite end of the bed performs a like function for the lever 5. A cover 47 is secured over the open outer end of the bumper box and 105 a fender bar 48 projects from said cover. When the piston rod is at the outer limit of its movement, it will be under the fender bar 48 and will be protected thereby against damage from falling objects. Moreover, the presence of the bar prevents persons standing in the path of the piston rod and suffering injury from the same as it moves outwardly.

110 Each carrier 30 has a pair of lugs 49 on 125 its top between which the hose-clamp puller is pivoted, and stop pins 50 are inserted through the lugs to support the pullers in inoperative position. The pullers, as will be readily understood from the drawings, each 130

consists of a pivoted shank or arm and an inverted yoke or fork at the free end of the shank to span the hose. The yoke preferably consists of two inverted L-shaped members 51 having their cross arms overlapped on the free end of the shank and secured thereto by a bolt 53, the bolt passing through slots 51^a in said cross arms whereby the yokes may be adjusted to the diameter of the hose in an obvious manner.

One carrier has secured to its inner end a block 54 which constitutes a holder for the train-pipe-coupler head and has formed in its upper side a recess 55 which varies in form accordingly as it is intended to receive the air-line head, the steam-line head, or the signal-line head. The coupler-head may be held down in the recess in any convenient or preferred manner, and in Figs. 7 and 8 we have shown a latch bar 56 pivoted for horizontal movement at one end on top of the holder in position to extend across the recess and have its free end engaged under a keeper 57 secured rigidly on the top 25 of the holder block. In Figs. 10 and 11, we have shown a bar 58 held at one end by a headed stud 59 and constructed at its opposite end with a notch 60 to receive the upper end of a threaded pin 61 mounted on the 30 side of the holder block. A hand wheel 62 is fitted on the upper extremity of the pin 61 and is turned home against the forked or notched end of the bar clamp the same across the coupler head.

The carrier at the opposite end of the machine carries a nipple-stripper which is best shown in Fig. 9 and comprises a base 63 secured firmly to the carrier and a part 64 of circular cross-section which projects horizontally from the base and is adapted to enter the nipple or fitting in the end of the hose remote from the coupler head. The part 64 is tubular as clearly shown and its free end is tapered, as at 65, whereby it may more readily enter the nipple, and within the tubular member, immediately adjacent the tapered free end thereof, is pivotally secured the stripper dog 66 which extends longitudinally of the tube away from the free end of the same. This dog is adapted to project, at its free end, through the longitudinal slot 67 in the tube 64 and a stop lug 68 is formed on the pivoted end of the dog to engage against the adjacent end wall 50 of the slot and thereby limit the outward movement of the free end of the dog, the said free end of the dog being given a claw-like form, as shown at 69, so that it may readily engage the end of the nipple or fitting. It will be understood that the device is pushed through the nipple or fitting until the dog clears the inner end thereof whereupon the dog is swung outwardly so that its claw or free end will engage the end of the 65 nipple after which the puller is drawn

longitudinally so that the nipple will be stripped from the hose. To swing the dog into the nipple-engaging position, we provide the plunger 70 within the tubular member 64 and the head 71 of this plunger has a beveled end or side upon which the dog rests. Movement of the plunger toward the dog will obviously raise the latter so that it will project through the tube 64 and engage the nipple while movement of the plunger in the opposite direction will permit the dog to withdraw by gravity. To effect movement of the plunger, we provide a lever handle 72 which is mounted in and projects upwardly from the base 63 and has its lower end engaged in an opening 73 in the plunger so that as said end of the handle is rocked in one or the other direction the plunger will be slid in the same direction. A spring 74 is coiled around the plunger between a stop ring 75 in the tube and an abutment shoulder 76 on the plunger, the spring holding the plunger head 71 in engagement with the dog 66 and the stop ring being slipped into the tube and held by a set screw so that it may be adjusted to regulate the tension of the spring as may be desired. In assembling a nipple with a hose, the dog 66 is not necessary and the holder 77, shown in Fig. 12, may be employed, this holder being also somewhat shorter than the nipple extractor.

The holder 77 is carried by a base 78 the end of which presents an abutment which receives the thrust of the fitting due to the resistance offered by the hose. The holder is circular in cross section and is constructed with longitudinal grooves or slots 110 to accommodate spring fingers 111 which are adapted to bind against the inner circumferential wall of the fitting and thereby firmly hold the same, the springs being held in place by having one end, with the end of the holder, fitted snugly in a socket in the end of the base. The end of the hose in which the nipple or fitting is to be inserted is not always in exact axial alinement with the holder and we provide means for adjusting the holder to meet the conditions. The base 78 is pivoted to the carrier 30 and may move pivotally as it is over a slot 28 in the top of the bed. A wedge 112 is arranged between the back of the base 78 and the opposed face of the carriage, and is constructed with an overhanging lip 113. A set screw 114 is mounted in the lip 113 and adapted to engage in a threaded socket in the base, washers 115 being fitted around the screw between the base and the lip, as shown. The base is adjusted pivotally to permit the holder to properly engage the hose after which the wedge is forced between the base and the carriage. The proper number of washers are then inserted to maintain the distance between the base and 120

the lip 113 whereupon the screw 114 is turned home to hold the parts together.

Between the carriers, at the center of the bed of the machine, is a hose-clamping mechanism by which the hose of the coupling is held during both the stripping and assembling operations. This mechanism comprises a lower or fixed clamp 79 which is rigid upon the bed and has its upper working face provided with transverse corrugations 80, and an upper clamp 81 having its under working face provided with corrugations 82 mating with the corrugations 80. Rising from the rear portion of the sides of the clamp 79 are guides 83 between which plays the arm 84 which carries the clamp 81 and is in turn carried by the upper end of a piston rod 85 rising from a piston 86 within a vertically disposed cylinder 87 located at the rear of the bed. Motive fluid is admitted to the cylinder 87 through a feed pipe 88 which is in communication through the four-way valve 17 with the main supply pipe 15, said valve being provided with an exhaust port 17a. The valve 17 is actuated by a rock shaft 89 disposed transversely in the bed and projecting through the front side thereof, a handle 90 being secured on the front end of the shaft so that all operations may be controlled from the front of the machine. When a hose is to be stripped of its head and nipple, it is held by and between the clamps 79 and 81 and the mating corrugations effectually secure it, the crimping of the hose being of no moment inasmuch as the hose is stripped of its fittings because it has lost its efficiency whereas the metal fittings may be further used with another hose. When the hose is to be released, fluid is admitted below the piston 86 and the piston moved upwardly and the upper clamp, consequently, raised. If the fluid be withdrawn, gravity will cause the piston and the clamp to drop so that the hose will be held, and if fluid be admitted above the piston the hose will be firmly secured. When new fittings are to be assembled with a hose, the corrugated working faces of the clamps 79 and 81 are rendered inoperative by employing auxiliary jaws to support the hose without pinching it and in such a manner that it may remain fully distended. The upper auxiliary jaw 91 consists of an elongated block having a longitudinal groove 92 in its lower side to fit over the hose, while on the upper side of the block are corrugations 93 which interengage with the corrugations on the clamp 81 and adjacent the ends of the block overhanging lugs 94 rise therefrom to fit around the side edges of the clamp 81, set screws 95 being mounted in the upper ends of the lugs to bind upon the clamp and secure the auxiliary jaw firmly thereto. The lower

auxiliary jaw comprises two blocks 96 adapted to rest on the bed at the ends of the clamp 79 and provided each with a longitudinal groove 97 in its upper side to receive the hose. These blocks are connected by a strap 98 which fits around the front end of the clamp 79 and maintains the blocks in proper position, set bolts 99 being mounted in the strap 98 and turned home against the clamp 79, if desired, to aid in holding the parts against displacement. The rear edge 100 of the jaw 91 is disposed somewhat lower than the front edge thereof and the blocks 96 have their rear sides 101 carried to a higher plane than their front edges and the clamp 79 to abut the edge 100 when the jaws are in engagement with a hose, the meeting of the edge 100 with the edges 101 limiting the closing movement of the jaws so that the hose will not be pinched.

Between the hose-supporting devices and each carrier is a hose-clamp shaper consisting of a pair of jaws 102 rising from slides 103 mounted in transverse ways in the bed and engaged with right and left threads 104 upon screws 105 mounted in bearings at the ends of the ways and equipped with hand wheels 106 at the front of the machine. Formers 107 are provided on the jaws 102 and are removable so that the securing bolts 95 may be engaged through openings 102a adjacent either side of the jaw whereby the formers may be adjusted to hose of different lengths. Obviously, by turning the hand wheels 106 the jaws 102 may be made to recede or to approach so that the formers will embrace the hose clamp. When the hose clamps are stripped from the hose, they are frequently distorted and must be reshaped before being applied to a new hose. In our present machine, the hose clamps are reshaped upon the hose so that a very material saving of time is effected, and, by properly manipulating the screws, the clamps will be supported in proper relation to the hose while the fittings are being forced into the same, and are prevented from spreading while the closing bolts are being inserted and secured.

Motors 115 may be substituted for the hand wheels 106. These motors may be of any preferred construction and are mounted on the back of the bed, being fed by a pipe 116 coupled directly to the main supply pipe 15, as shown in Figs. 15 and 16. Each motor has a stem 117 extending from its controlling valve, which stem is engaged with the upper end of a crank arm 118 on the rear end of a rock shaft 119 journalled in and extending through the bed of the machine. On the front end of each rock shaft is a handle 120 whereby the shaft may be set to start or stop the adjacent motor.

In stripping a hose of its fittings, the hose is secured between the clamps 79 and

81 and the carriers 30 are moved inwardly so that the nipple-puller will be engaged in the nipple and the coupler-head secured in the holder as hereinbefore set forth. The 5 clamp pullers are then engaged over the ends of the hose immediately behind the clamps, after which the piston 38 is caused to travel in the proper direction to effect outward travel of the carriers whereby the coupler 10 head, the nipple, and the clamps will be quickly drawn from the hose. In assembling the fittings with a new hose, the hose is placed between the jaws 91 and 96 with the hose clamps around its ends. The jaws 15 102 are then moved inwardly so that the formers will embrace said clamps and support them in proper angular relation to the hose, after which the carriers are moved inwardly so that the head and nipple carried 20 by them will be forced into the respective ends of the hose.

In Figs. 17 to 21, the clamp-formers are shown as comprising carriers 121 slidably engaging ways in the top 27 of the bed and 25 fitted to the threaded portions of the screws 105. From the top of each carrier rises an angular stud or post 122 of less area than the top of the carrier whereby the top of the carrier forms a rest or support for a 30 shaper jaw 123 which is provided with a central opening of the same configuration as the post 122 and adapted to snugly receive the post whereby twisting movement of the jaw will be prevented. Each jaw is provided on one face with a projection 124 having a concave recess 125 whereby it may fit 35 readily around the hose clamp, the projection being located at one side of the central longitudinal line of the jaw. This construction permits the jaw to be readily set 40 according to the length of the hose about which the clamp is to be set. As shown in Fig. 18, the former will act on hose of one length. If the jaws be lifted from the posts, 45 then inverted, and then reengaged over the posts, they will be set for hose of another length, as shown in Fig. 19. Each shaper jaw is provided, on the face remote from the 50 projection 124, with a rib or tooth 126 which is narrower than said projection 124 and is disposed on the central longitudinal line of the jaw.

Many hose are torn in two, the rubber part of the hose being too short to be caught 55 and held by the clamps 79 and 81, and in this event the teeth 126 are run up ahead of the clamps onto the hose, holding it while the fitting is pulled out.

Having thus fully described our invention, 60 what we claim as new and desire to secure by Letters Patent of the United States is:—

1. In a machine of the class described, the combination of a hose support, fittings, carriers arranged at opposite sides of said 65 support and movable toward and from the

same, and means between the support and the carriers for compressing clamps about the hose.

2. In a machine of the class described, the combination of a hose support, fittings, carriers arranged at opposite sides of the support and movable toward and from the same, and cooperating formers located between the hose support and the carriers and movable transversely of the hose support to cause clamps to embrace the ends of a hose 75 secured in the support.

3. In a machine of the class described, the combination of a bed, a hose support on said bed, carriers mounted on the bed at opposite sides of the support and movable longitudinally of the bed whereby to strip fittings from or insert them in a hose secured in the hose support, pairs of slides mounted transversely in the bed between the hose 80 support and the carrier, jaws rising from said slides, formers fitted to said jaws and adapted to embrace clamps on the ends of a hose secured in the hose support, and means for causing the jaws to travel simultaneously in opposite directions.

4. In a machine of the class described, the combination of a bed, a fixed clamp thereon, guides rising from said clamp, a vertically movable support mounted on the bed, an arm projecting laterally from said support and playing between said guides, a clamp carried by said arm to cooperate with the fixed clamp, and means on the bed to operate the movable support.

5. In a machine of the class described, the combination of a bed, carriers mounted on top of the bed, a cylinder mounted in the bed, a piston in said cylinder, a piston rod extending from said piston, a vertical lever fulcrumed between its ends in the bed, the lower end of said lever being connected with the piston rod and the upper end of the lever being connected with one of the carriers, a second vertical lever fulcrumed between its ends in the bed and having its upper end connected with the other carrier, and a link pivoted at one end to the lower end of the second lever and at its opposite end to the first lever above the fulcrum thereof.

6. In a machine of the class described, the combination with cooperating clamping jaws, of auxiliary jaws adapted to be engaged with the clamping jaws and render the working faces thereof inoperative, one of said auxiliary jaws having overhanging lugs to engage around and over the ends of the upper clamping jaw, and set screws mounted in the said lugs and binding on the clamping jaw.

7. In a machine of the class described, the combination of upper and lower clamping jaws, and auxiliary jaws to be engaged therewith and render the working faces thereof inoperative, the lower auxiliary jaw com-

prising two blocks to be disposed at the ends of the lower clamping jaw and a strap connecting said blocks.

8. In a machine of the class described, the combination of upper and lower clamping jaws, and auxiliary jaws to be engaged therewith, said auxiliary jaws having longitudinally grooved opposed working faces and provided at their rear sides with longitudinal abutting elements whereby they may embrace a hose without compressing the same.

9. In a machine of the class described, the combination of a bed, working elements mounted thereon, means for operating said elements including a longitudinally movable piston rod in the lower portion of the bed, a bumper box on the bed through which the piston rod plays, means within the bumper box to cushion the in stroke of the piston rod, and a fender bar projecting from the bumper box over the path of the piston rod.

10. In a machine of the class described, the combination of a coupler-head holder having a recess to snugly receive the coupler head, a latch bar mounted on the holder to extend over said recess, and means for securing said latch bar in operative position.

11. In a machine of the class described, the combination of a hose support, fitting carriers arranged at opposite sides of said support and movable toward and from the same, one of said carriers carrying a nipple

pulley comprising a tubular body having a longitudinal slot near one end, a dog pivotally mounted in the body and adapted to project through said slot, means for swinging the dog outwardly, and means for limiting the outward swinging movement of the dog.

12. The combination of a carrier, a base pivoted to the carrier, a fitting holder secured to the base, a wedge inserted between the end of the base and the opposed side of the carrier and provided with a lip overhanging the base, washers inserted between the base and said lip, and a set screw fitted through said lip and the washers into the base.

13. The combination of a bed, screws mounted transversely in the bed, slides in the bed engaging said screws to be moved thereby, fluid pressure motors mounted on the bed and operatively connected with the screws, rock shafts mounted in the bed adjacent the motors, crank arms on the rear ends of the rock shafts connected with the motors, and handles on the front ends of the rock shafts.

In testimony whereof we hereunto affix our signatures.

WILLIAM D. FAIDLEY, JR.
JOHN W. MORRIS.
SAMUEL A. PATTERSON.
